CLAIM

The ornamental design for a charger for electric cleaner, as shown and described.

DESCRIPTION

FIG. 1 is a right-side perspective view of a charger for electric cleaner showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front view of the charger for electric cleaner shown in an example state of use wherein the charger for electric cleaner is shown in an extended position.

The broken lines in the figures depict portions of the charger for electric cleaner that form no part of the claimed design.

1 Claim, 7 Drawing Sheets
